SWITCH FOR DIRECTION INDICATORS

Sven Johan Eugen Asklund, Stockholm, Sweden

Application May 12, 1931, Serial No. 536,829
In Sweden May 16, 1930

5 Claims. (Cl. 200—59)

The present invention relates to switches for direction indicators for motor vehicles. More particularly the invention relates to such direction indicators which comprise a number of electromagnetically actuated signals adapted to be brought in signal positions by means of an electric switch arranged within reach of the driver.

The invention has for its object to provide a circuit controller, which can easily be operated with the fingers of the hand holding the steering wheel without interfering with the steering, and by which the signal is automatically released from its swung up position through the returning movement of the steering column after passing a curve.

To the attainment of this object the invention consists substantially therein, that a signalling switch is pivoted on a receptacle, which is mounted on the steering column adjacent to the steering wheel, said receptacle containing signal restoring members of unidirectional operation and an abutment connected with the steering wheel and arranged in the path of the signal restoring members.

Other objects and novel details of construction will be more fully described hereinafter and pointed out in the claims.

The invention will now be more closely described with reference to the accompanying drawing, in which is shown a diagrammatic view partly in section of an embodiment of the invention.

In the drawing 1 and 2 indicate two electromagnetic direction signal devices, the signal device 1 comprising an indicating arm 3 which is pivoted at 4 and controlled by a solenoid 6 and the signal device 2 comprising an arm 5 which is pivoted at 4' and controlled by a solenoid 7. Each solenoid cooperates with a plunger 8, ⁸¹ which is connected with the arms 3, 5 by means of a link 9, 10. When the coil 6 is energized the plunger 8 is attracted and pulls the link 9 into the position shown whereby the arm 3 is brought into signal position. As soon as the current through the coil 6 ceases the corresponding parts will take up the position shown on the right hand part of the figure. The driver's switch comprises two normally open contacts 11, 12 and 13, 14, of which the contacts 11, 13 are connected to earth, i. e. the frame of the motor vehicle. The contact 12 is over a wire 15 connected to the solenoid 6 and the contact 14 over a wire 17 to the solenoid 7. The wires 15, 17 are also connected to branch wires 19, 23, which lead over normally open contacts 20, 21 and 24, 25 to earth. The contacts

20, 21 and 24, 25 are adapted to be closed in the signal position of the device, i. e. when the plunger 8 takes up its attracted position in which case a metallic projection 22 disposed on the plunger 8 enters between the contacts 20 and 21 thereby constituting a conducting bridge between said contacts. The opposite terminals of the coils 6 and 7 are connected to wires 27 and 28 which lead to the contacts 29 and 30 of two release devices constituted by two switches 31 and 32 disposed in a particular manner which will be more closely described in the following but which have the characteristic property that they are normally closed but adapted to be opened by an abutment 33 disposed on the steering gear, when the wheel is turned in a direction towards the straight ahead position from a swung out position corresponding to the driving direction signalled. The opposite contacts of the switches are connected to a normally closed contact 36, 37 which is connected to the positive terminal of a battery 11 the opposite terminal of which is grounded, i. e. connected to the frame.

The hand wheel 48 with its rod is rotatably mounted in usual manner in the steering column 49. On this column there is mounted a sleeve-shaped member 50 of insulating material, such as bakelite. On the drawing a portion of said sleeve has been broken away so as to show more clearly some of the parts enclosed therein. The connection from the contacts 31, 32 to earth is constituted by a metallic band 51 of cylindrical shape and secured to the inside of the sleeve 50. To this band is connected a metallic leaf spring 36 cooperating with the contact 37 disposed in the sleeve 50 and on the outside thereof connected to the plus pole of the battery. Extending through an aperture in the sleeve 50 there is disposed a push member 52 adapted to break the contact between parts 36 and 37 upon being actuated.

The switches 31 and 32 are constituted by U-shaped metallic pieces which are pivoted on the band 51 at 53 and 54 respectively. They are actuated by helical springs 55, 56 the ends of which engage the band and the switch members 31, 32 in such a manner that they tend to hold the parts 31, 32 in the position shown to the left bearing against the contacts 29, 30. In the top portion of each piece 31, 32 there are pivotally mounted at 57, 58 two detents 59, 60 which preferably are made of insulating material. The detents 59, 60 are normally held in a position parallel with the bottom side of the pieces 31, 32 by means of helical springs 61, 62 the ends of which are bearing in suitable manner against the detents 59, 60.

and the bottom sides of the parts 31, 32. The abutment 33 is here constituted by a rigid metal bar secured to a split ring 63 the ends 64, 65 of which are squeezed between the abutment 33 and 5 a reinforcing disc 66 which parts are held together by means of suitable bolts. The ring 63 is mounted tightly on the lower cylindrical portion of the steering wheel so as to follow the movements of the steering gear. Any other suitable 10 manner of mounting the part 33 will, of course, be within the scope of the invention.

From the drawing it is evident that the turning of the steering wheel in such a direction that the abutment 33 is moved towards the centre of the 15 figure will actuate the detent 60 which is catching the part 32 and forcing it to take up an inclined position until the abutment 33 has passed the detent 60. In this case the part 32 will be 20 out of contact with the contact piece 30 which is secured to the inside of the sleeve 50 and connected to the wire 41. In this case the coil 7 will evidently be deenergized. If, on the other hand, the wheel is turned further on in the same direction so that the abutment 33 is passing the 25 detent 59, this detent will yield and swing on its pivot 57 against the action of the spring 61 until the abutment 33 has passed. During this passage a metallic contact is uninterruptedly maintained 30 between the bar 51 and the contact 29 whereby the wire 39 leading to the coil 6 is in metallic connection with the positive pole of the battery.

The contacts 11, 12 and 13, 14 are constituted by metal springs secured to the inside of the insulating sleeve 50. Their upper ends are bent 35 somewhat outwards and are adapted to cooperate with semi-annular metal members 67 and 68 which are pivoted at 69 and 70 respectively on the sleeve 50. By this disposition it is evidently quite easy to hold the hand-wheel by for instance the 40 right hand and at the same time touch the member 68 by the tips of the fingers of the same hand whereby the contacts 13, 14 will be closed and the coil 7 energized, provided the switch 32 is closed.

The signal devices 1 and 2 are preferably disposed in the following manner. The top of the 45 coil 6 is provided with an end piece 69 carrying an upwardly extending arm 70 on which the arm 3 is pivoted at 4. The corresponding parts on the right hand side are designated 71 and 72. 50 To the bottom of the coil frame there is secured a box shaped part 73, 74 in which the contacts 20, 21 and 24, 25 respectively are disposed as shown. On the bottom of the box 73, 74 there is provided an insulating piece 75, 76 on which the 55 contact 42, 44 is mounted in a shape of a leaf spring the end of which cooperates with the contact 43, 45 which is designed as a bolt provided with nuts on the outside and the inside of the box 73, 74.

60 It is quite evident that the present invention is not restricted to the case that the arm 3, 5 is electromagnetically locked in its swung up position by the holding circuit arrangement. It is also conceivable that the arm 3, 5 be held in 65 swung up position by a mechanical detent of usual construction which cooperates with a special release magnet which is normally deenergized but energized when the abutment 33 of the steering gear is moving in a direction towards 70 the straight ahead position from the swung out position signalled by the appertaining arm.

The positions of the switches 31, 32 along the bar 51 may, of course, be adjusted to suit the 75 conditions, i. e. the angular positions of release

may be brought more or less close to the straight ahead position of the steering gear.

I claim:—

1. In a signalling system for motor vehicles having a steering column and a steering wheel rotatably mounted therein, a receptacle mounted on and surrounding the steering column adjacent to the steering wheel, a semi-annular, manually operable signalling switch member pivoted on the receptacle adjacent to the steering 10 wheel and arranged coaxially thereof, a signal restoring device accommodated within said receptacle, an actuating member of unidirectional operation connected with said restoring device, and an abutment rigidly connected with said steering wheel and projecting inside said receptacle into the path of said actuating member. 15

2. In a direction signalling system for motor vehicles having a steering column and a steering 20 wheel rotatably mounted therein, a receptacle mounted on and coaxially surrounding the steering column adjacent to the steering wheel, a semi-annular, manually operable signalling switch member coaxial with said receptacle and pivoted thereon adjacent to the steering wheel, 25 a signal restoring device accommodated within said receptacle, an actuating member of unidirectional operation connected with said restoring device, and an abutment rigidly connected with said steering wheel and projecting inside said 30 receptacle into the path of said actuating member.

3. In a direction signalling system for motor vehicles having a steering column and a steering 35 wheel rotatably mounted therein, a receptacle mounted on and coaxially surrounding the steering column adjacent to the steering wheel, two pivots mounted at substantially diametrically opposite points at the top of the receptacle, a semi-annular, manually operable signalling switch 40 member conforming with the upper edge of said receptacle and mounted on said pivots, a signal restoring device accommodated within said receptacle, an actuating member of unidirectional operation connected with said restoring device, 45 and an abutment rigidly connected with said steering wheel and projecting inside said receptacle into the path of said actuating member.

4. In a direction signalling system for motor vehicles having a steering column and a steering 50 wheel rotatably mounted therein, a receptacle formed as a hollow cylinder mounted on and coaxially surrounding the steering column adjacent to the steering wheel, two pivots mounted at substantially diametrically opposite points at 55 the top of the receptacle, a semi-annular, manually operable switch member mounted on said pivots to swing between the underside of the hand wheel and the outside of the receptacle, a signal restoring device accommodated within 60 said receptacle, an actuating member of unidirectional operation connected with said restoring device, and an abutment rigidly connected with said steering wheel and projecting inside said receptacle into the path of said actuating member.

5. In a direction signalling system for motor vehicles having a steering column and a steering 70 wheel rotatably mounted therein, a receptacle formed as a hollow cylinder mounted on and coaxially surrounding the steering column adjacent to the steering wheel, two pivot groups disposed at substantially diametrically opposite 75 points at the top of the receptacle, two semi-

annular, manually operable, mutually independent switch members mounted on opposite sides of said receptacle on said pivot groups to swing between the underside of the hand wheel and the outside of the receptacle, a signal restoring device accommodated within said receptacle, an

actuating member of unidirectional operation connected with said restoring device, and an abutment rigidly connected with said steering wheel and projecting inside said receptacle into the path of said actuating member.
